STOP MOTION FOR LOOMS

Odie F. Doss, Sycamore, Va.

Application December 11, 1946, Serial No. 715,363

7 Claims. (Cl. 139—290)

1

This invention relates to a stop motion for a loom and has for its primary object to prevent the weaving of faulty goods.

Another object is to arrest the flow of power to a power driven loom should the clamp and cutter fail to grip the severed filling during the period of substitution of a filled bobbin for an empty bobbin.

In the textile industry many looms are equipped with a transfer mechanism for extracting an empty bobbin from the shuttle and replacing it with a filled bobbin all operating automatically so as to avoid interruption in the weaving operations. Most such looms are equipped with what is known in the industry as a filling knife or clamp and cutter which during the operation of the transfer mechanism is adapted to advance toward the shuttle, sever the filling from the empty bobbin and grip the severed filling, to hold it in position to resume weaving. In certain instances the clamp fails to grip the filling with the result that continued operation of the loom produces faulty goods and hence loss of production results.

This invention has for another object to arrest the motion of the loom should the clamp fail to grip the filling as it is supposed to do.

The above and other objects may be attained by employing this invention which embodies among its features a shaft mounted to rock about its longitudinal axis, a lever carried by the shaft to be engaged by the clamp and cutter advancing means as the clamp and cutter is advanced thereby toward the shuttle of a loom and thus to rock the shaft in one direction, said lever being adapted to be engaged by the clamped filling when the clamp and cutter is retracted thus to rock the shaft in the opposite direction and means actuated by the shaft to interrupt the flow of power to the loom when the shaft is rocked with the advance of the clamp and cutter and to restore the flow of power to the loom when the shaft is rocked in a reverse direction.

Other features include a mercury switch actuated by the shaft to interrupt the flow of power when the shaft is rocked with the advance of the clamp and cutter and to restore the flow of power to the loom when the shaft is rocked in a reverse direction and a barrier within the mercury switch to retard the flow of mercury from one end thereof to the other, thus to avoid the instantaneous interruption of the flow of power to the loom.

Still other features include counterweights carried by the shaft to hold it in either position.

In the drawings:

Figure 1 is a front view of a portion of the transfer mechanism of a loom illustrating in detail the clamp and cutter and showing this improved stop motion associated therewith;

Figure 2 is an end view of Figure 1; and,

Figure 3 is a top plan view of Figure 2.

10. Referring to the drawings in detail, the clamp and cutter mechanism designated generally 10 is suspended from a bar 11 which projects laterally from the transfer mechanism in spaced parallel relation with the lay of the loom in a conventional manner. Suspended from the bar 11 adjacent its free end is a conventional yoke 12 having depending arms carrying adjacent their lower ends a guide track 13 in which a carriage 14 for the clamp and cutter is slidably mounted. The clamp and cutter designated generally 15 is of conventional form and carries adjacent its rear end a laterally extending pin 16 by which the jaws 17 and 18 of the clamp and cutter are opened and closed through the medium of a cam 19 carried on the end of the clamp and cutter actuating arm 20. The mechanism so far described is of conventional form and is employed in connection with the transfer mechanism of a conventional loom to sever the filling from an empty bobbin and hold it in position to resume the weaving operation after a filled bobbin has been replaced in the shuttle, it being understood that the knife or clamp and cutter 15 advances and by reason of the movement of the arm 20 toward the shuttle as suggested in Figure 3, severs the filling and grips it between the jaws 17 and 18.

This invention cooperates in conjunction with the filling knife or clamp and cutter 15 and comprises a support 21 which is bolted or otherwise attached as at 22 to the guide 13.

40. A second arm or standard 23 is bolted or otherwise secured at 24 to the opposite end of the yoke 12 and both standards 21 and 23 are provided near their upper ends with aligning openings 45 for the reception of a rock shaft 25. One end of this rock shaft is threaded as at 26 and carries clamp nuts 27 between which a depending arm 28 is supported for movement with the shaft 25. Fixed adjacent the lower end of the arm 28

50. are yielding clamp jaws 29 the purpose of which will be more fully hereinafter explained. A collar 30 is attached as by set screw 31 to the end of the shaft 25 opposite the threaded end 26 to bear against the standard 23 and prevent the shaft 55 from being withdrawn from its position within

the standards. A lever arm 32 is fixed to the shaft 25 and depends therefrom, so that its lower end lies in the path of movement of the pin 16 of the clamp and cutter 15. It will thus be seen that when the clamp and cutter is advanced toward a shuttle which is being refilled, the arm 32 will be engaged and the shaft 25 rocked in its bearings. It is also to be noted that the lower end of this arm lies in the path of the severed filling when the latter is being moved under the influence of the clamp 15 away from the shuttle, so that with the return stroke of the clamp and cutter 15 the shaft 25 will be rocked to its initial position. If, however, the clamp of the clamp and cutter 15 fails to grip the filling thread, the shaft 25 will not return to its initial position.

In order to effect the control of the loom through the rocking of the shaft 25 I employ a mercury switch designated generally 33 which is adapted to be controlled by the movements of the shaft 25. In its present embodiment the switch 33 comprises a glass envelope 34 which is clamped between the clamp arms 29 at the lower end of the arm 23 and sealed in one end of this envelope 34 is a pair of spaced parallel electrodes 35 and 36 to the outer ends of which are soldered or otherwise connected as at 37 and 38 suitable conductors 39 and 40 leading through a cable 41 respectively to a source of electrical energy and to the drive motor of the loom. The envelope 34 contains a conducting fluid 42 such as mercury so that when the switch 33 is rocked about the axis of the shaft 25, contact of the mercury with the electrodes 35 and 36 will be made or broken according to the direction of movement of the shaft.

In order to retard the flow of the fluid 42 from one end of the envelope 34 to the other, and hence retard the action of the switch, I provide a barrier 43 within the interior of the envelope 34 in which an aperture 44 is formed through which the fluid 42 must flow as the envelope is tilted from one side to the other. The speed of action of the switch is governed by regulating the size of the opening 44 and hence the rapidity with which the fluid may move from one end of the envelope to the other.

In order to hold the rock shaft 25 in one or the other of its positions and yet to permit it easily to be thrown to the opposite position, I provide a pair of counterweights 45 and 46 which are clamped to the shaft 25 by set screws 47 so that they may easily be adjusted. A stop member 48 is bolted as at 49 to the yoke 12 and extends upwardly and forwardly as illustrated in Figure 2. The upper end of this stop member is provided with a laterally extending arm 49 which lies in a plane parallel with the shaft 25 in spaced relation thereto, and in the path of movement of the counterweights 45 and 46, so as to limit their movements about the axis of the shaft 25, and consequently restrict the arc through which the shaft may rock.

In use it will be understood that one terminal of one of the conductors 39 or 40 is coupled with a source of power while the other terminal of the other conductor is coupled with the drive motor of the loom. With the envelope 34 in the dotted line position shown in Figure 2 the current will flow from one electrode through the conducting fluid to the opposite electrode and thus provide an uninterrupted flow of power to the loom motor. As the clamp and cutter 15 advances toward the shuttle to sever the filling from an

empty bobbin and grip it, the lever 32 will be engaged by the pin 16 so as to rock the shaft 25 into the position illustrated in the full lines in Figure 2, thus tipping the envelope 34 into the full line position illustrated in Figure 2 so as to cause the fluid 42 to start to flow through the constricted passage 44 toward the end of the envelope opposite the electrodes 35 and 36. If the clamp 15 grips the filling as it is supposed to do, it will return to its initial position and cause the filling to engage the lever arm 32 and restore the parts to their initial position before the fluid 42 has broken contact with the electrodes 35 and 36. If for any reason the clamp and cutter 15 fails to grip the filling it will be obvious that upon its return stroke no movement of the lever 32 will result and consequently the envelope 34 will remain in the full line position illustrated in Figure 2, thus permitting the fluid 42 to break contact with the electrodes 35 and 36 and thus interrupt the flow of power to the drive motor of the loom and hence effecting the stoppage of the loom.

From the foregoing, it is obvious that stopping of the loom is not effected except when the pause of the envelope 34 exceeds a predetermined period of time occasioned by the failure of the clamp and cutter to grip the filling.

Obviously the switch 33 may be placed between the jaws 29 in a reverse position so that the electrodes 35 and 36 will project in a direction reverse to that shown in the drawings. As a result, the device may be employed in conjunction with a conventional loom stop motion or any suitable relay which, when energized, will effect the stopping of the loom.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold the severed filling which includes; a shaft mounted to rock about its longitudinal axis; a lever carried by the shaft to be engaged by an element on the clamp and cutter actuating means as the clamp and cutter is advanced thereby toward the shuttle, thus to rock the shaft in a one direction; said lever being adapted to be engaged by the clamped filling when the clamp and cutter is retracted, thus to rock the shaft in the opposite direction; and means actuated by the shaft to interrupt the flow of power to the loom when the shaft is rocked with the advance of the clamp and cutter should the clamp fail to grip and hold the filling while the clamp and cutter is being retracted.

2. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold

the severed filling which includes; a shaft mounted to rock about its longitudinal axis; a lever carried by the shaft to be engaged by an element on the clamp and cutter actuating means as the clamp and cutter is advanced thereby toward the shuttle, thus to rock the shaft in one direction; said lever being adapted to be engaged by the clamped filling when the clamp and cutter is retracted, thus to rock the shaft in the opposite direction; and a mercury switch actuated by the shaft to interrupt the flow of power to the loom when the shaft is rocked with the advance of the clamp and cutter should the clamp fail to grip and hold the filling while the clamp and cutter is being retracted.

3. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold the severed filling which includes; a shaft mounted to rock about its longitudinal axis; a lever carried by the shaft to be engaged by an element on the clamp and cutter actuating means as the clamp and cutter is advanced thereby toward the shuttle, thus to rock the shaft in one direction; said lever being adapted to be engaged by the clamped filling when the clamp and cutter is retracted, thus to rock the shaft in the opposite direction; a mercury switch actuated by the shaft to interrupt the flow of power to the loom when the shaft is rocked with the advance of the clamp and cutter should the clamp fail to grip and hold the filling while the clamp and cutter is being retracted, and a barrier within the mercury switch to retard the flow of mercury therein.

4. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold the severed filling which includes; a shaft mounted to rock about its longitudinal axis; a lever carried by the shaft to be engaged by an element on the clamp and cutter actuating means as the clamp and cutter is advanced thereby toward the shuttle, thus to rock the shaft in one direction; said lever being adapted to be engaged by the clamped filling when the clamp and cutter is retracted, thus to rock the shaft in the opposite direction; means actuated by the shaft to interrupt the flow of power to the loom when the shaft is rocked with the advance of the clamp and cutter should the clamp fail to grip and hold the filling while the clamp and cutter is being retracted, and means carried by the shaft yieldingly to hold it in either rocked position.

5. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold the severed filling which includes; a shaft mounted to rock about its longitudinal axis; a lever carried by the shaft to be engaged by an element on the clamp and cutter advancing means as the

clamp and cutter is advanced thereby toward the shuttle, thus to rock the shaft in one direction; said lever being adapted to be engaged by the clamped filling when the clamp and cutter is retracted, thus to rock the shaft in the opposite direction; means actuated by the shaft to interrupt the flow of power to the loom when the shaft is rocked with the advance of the clamp and cutter should the clamp fail to grip and hold the filling while the clamp and cutter is being retracted, and counterweights carried by the shaft yieldingly to hold it in either rocked position.

6. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold the severed filling which includes; a shaft mounted to rock about its longitudinal axis; a lever carried by the shaft to be engaged by an element on the clamp and cutter actuating means as the clamp and cutter is advanced thereby toward the shuttle, thus to rock the shaft in one direction; said lever being adapted to be engaged by the clamped filling when the clamp and cutter is retracted, thus to rock the shaft in the opposite direction; a mercury switch actuated by the shaft to interrupt the flow of power to the loom when the shaft is rocked with the advance of the clamp and cutter should the clamp fail to grip and hold the filling while the clamp and cutter is being retracted, and counterweights carried by the shaft yieldingly to hold it in either rocked position.

7. In a power driven loom having a shuttle; a transfer mechanism for extracting an empty bobbin from the shuttle and replacing it with a filled bobbin and a clamp and cutter adapted to advance toward the shuttle, sever the filling from the empty bobbin and grip the severed filling; a stop motion to interrupt the operation of the loom should the clamp fail to grip and hold the severed filling which includes; a shaft mounted to rock about its longitudinal axis; a lever carried by the shaft to be engaged by an element on the clamp and cutter actuating means as the clamp and cutter is advanced thereby toward the shuttle, thus to rock the shaft in one direction; said lever being adapted to be engaged by the clamped filling when the clamp and cutter is retracted, thus to rock the shaft in the opposite direction; a mercury switch actuated by the shaft to interrupt the flow of power to the loom when the shaft is rocked with the advance of the clamp and cutter should the clamp fail to grip and hold the filling while the clamp and cutter is being retracted, a barrier within the mercury switch to retard the flow of mercury therein, and counterweights carried by the shaft yieldingly to hold it in either rocked position.
